UNITED STATES PATENT OFFICE.

ERNEST E. HEINTZ, OF DETROIT, MICHIGAN, ASSIGNOR TO TERNSTEDT MANUFACTURING COMPANY, OF DETROIT, MICHIGAN, A CORPORATION OF MICHIGAN.

WINDOW-REGULATOR.

1,398,693.

Specification of Letters Patent. Patented Nov. 29, 1921.

Application filed January 7, 1921. Serial No. 435,597.

To all whom it may concern:

Be it known that I, ERNEST E. HEINTZ, a citizen of the United States, residing at Detroit, in the county of Wayne and State of Michigan, have invented certain new and useful Improvements in Window-Regulators, of which the following is a specification.

This invention relates to window regulators, and has for its object a window regulator which is actuated by a lever sliding along the garnish rail of the window. It is primarily intended for application to closed automobile bodies.

The rear quarter window presents somewhat of a problem in applying the usual window regulator thereto. In fact, it has been such a problem that the majority of cars have not used a window regulator on the rear quarter window but have employed the old pull strap. Most window regulators are designed to have the crank handle directly in the middle of the window. This is a very unhandy and inconvenient arrangement with the rear quarter window as it brings the crank handle directly at the side of the seat. Those window regulators that have the raising lever forward of the center of the window would in a great many closed jobs interfere with some of the fixtures, such as the usual toilet case that is placed in a high grade car. It is the object of the present invention to provide a window regulator which obviates these objections by having a handle that runs along the garnish rail.

Furthermore, the window regulator is provided with such an arrangement of levers as to make the operation of raising and lowering the window extremely easy. The lever arrangement is such that the thrust and pull on the window is a substantially vertical line thrust at the center of the window rail and consequently the window will not bind or cramp in the window-ways to cause friction and difficulty in raising or lowering.

Another feature of this regulator is a special form of clutch which offers no resistance to any effort applied to the lever handle but which locks when effort is applied through the window as will more fully appear in the description following.

In the drawings,—

Figure 1 is an elevation of the inside of a

closed body with the trimming and lock-board broken away, showing the improved regulator applied to the rear quarter window.

Fig. 2 is a side elevation of the window regulator operating parts and handle, viewing the lock-board from the inside of the same.

Fig. 3 is a section on the line 3—3 of Fig. 2.

Fig. 4 is a section on the line 4—4 of Fig. 2.

Fig. 5 is a section taken on the line 5—5 of Fig. 7.

Fig. 6 is an elevation of the operating parts of the regulator showing the window in its dropped position.

Fig. 7 is a section on the line 7—7 of Fig. 5.

Fig. 8 is a section on the line 8—8 of Fig. 2.

Fig. 9 is a rear view of the supporting plate or cup showing the adjusting devices for the counterbalancing spring.

The regulator supporting plate is designated *a* and is screwed to the inside of the lock-board *b*. In back of this plate and in the front of the lock-board is a cup *c* in which is located the concaved washer *d* provided with the bolt and nuts *e* and fitted in to the supporting plate *a*. This washer forms a hub about which winds the spiral counterbalancing spring *f*. This washer is secured to the inner end of the spring by the hook *g* on the spring. This washer *d* is provided with teeth *h* (Fig. 9) with which is adapted to engage the catch *i* which is cut off at one side. When the catch is in the position shown in Fig. 9, it locks in the gullets of teeth *h* and prevents the hub from turning. When it is desired to tighten or loosen the counterbalancing spring this catch *i*, which is on the back of the cup *c* and exposed through the board *b*, may be readily reached by simply removing the trimming on the front of the board *b*. The catch may be then turned to bring the flat side adjacent the teeth *h*. This permits the hub to be turned by placing a tool therein.

The hub may be turned such a number of notches as is necessary to tighten or loosen the spring. Thereupon the catch *i* may be turned back into engagement between the teeth to hold the hub fixed. The other end of the spring is engaged by the stud *j* which

is fastened to the lever *k*. This lever *k* is fulcrumed on the hub bolt *e*. The lever *k* has its swinging end pivoted to the lever *m* which has one end secured to a check link 5 *n*, which is hung from the pivot *p* secured to the anchoring strip *x*. The lever *m* has its end of larger swinging arc pivoted to a short link *q* which in turn is pivoted by the pin and cotter *r* to the bottom rail *s* of the 10 window. The supporting plate *a* is countersunk at *t*, permitting the pin *j* to swing in the plate and wind up the counterbalancing spring when the window goes down.

Pivoted on the bolt *e* is a bell crank lever 15 *w* whose right hand arm 1 cooperates with a link *y* to form in effect a pair of toggle arms for thrusting on the window lifting lever *m*. When these toggle arms reach substantially a center line position, as shown in Fig. 2, the 20 pin and shoulder *z* prevent the toggle arms from throwing any further. This center position prevents any effort directed on the window lifting lever *m* from breaking the toggle. The consequence is that when the 25 window is in its upright position these toggle arms present an effective lock to hold it in this position without any other aid, such as the clutch presently to be described.

The position of the levers is such in the 30 lowermost position of the window as to effectively lock the window from jumping due to the jolting of the car. Note the position of the operating parts in Fig. 6. Any effort of the window to raise is resisted by the levers ultimately transmitting a straight line thrust on the link 2. This permits a cushion 100 of felt or rubber to be used at the bottom of the window travel and the window may be jammed thereinto and locked in anti- 40 rattling position by the levers being arranged so that one of them (2) assumes a dead center position to any thrust originating in the window.

Sufficient structure is now described to 45 name the functions and the grouping of the various levers and links. The lever *k* and the upper portion of the window lifting lever *m* form a pair of toggle levers folding up when the window is in the down position (see Fig. 6) and the toggle straightening out when in the upright position shown in Fig. 2. The straightening out or the breaking of the toggle is effected similarly by another pair of toggle arms *y* and 1 50 *z* thrusting on the same fixed pivot *e*. As is well known, toggle levers or arms convert a force striking the toggle at the knee and traveling through a considerable distance into a greater force at the ends of the toggle traveling through a less distance. In short, the leverage is considerably multiplied. This takes place in both sets of toggle arms. Hence the leverage is considerable. Furthermore, the toggle arms 1 and *y* secure the additional advantage of locking against any 65

endwise thrust brought thereupon. And additionally, the toggle lever *k*, in conjunction with the stud *j*, acts as a counterbalancing spring winding element.

The toggle arms, 1, *y*, are broken or 70 straightened out by the movement of the bell crank lever *w*. As the resistance arm of this lever is considerably shorter than the power arm it will be evident that here also the leverage increases. The end of this lever is 75 connected by the link 2 with a slide 3 which engages in the groove of the channelled track 4 screwed to the inside of the lock-board. This track comprises a channelled track having turned-over flanges 5, 6 (see Fig. 7). A 80 carriage 7 rides on this track which is provided with fiber rolls 8 that are riveted thereto and that run in the channel. Slotted fiber blocks 9 engage the under flange 6 of the track and straddle the same. The hooks 85 10 of the carriage engage over these blocks. A slotted fiber block 11 engages in the straddling position over the upper flange 5. A struck-in hook 12 engages over this block. These hooks 10 and 11 in combination with 90 the blocks securely lock the carriage on the track so that it can be disengaged therefrom only by sliding off the end. The slide 3 is locked loosely into the carriage when the carriage is assembled upon the track, as will 95 be seen from the position of the parts in Fig. 2. This slide 3 is provided with a pair of springs 13 anchored in the ends which engage over the prow at each end of the slide and tend to force the disks or rolls 14 toward 100 each other. Notice, however, that the upper surface of the slide 3 that supports the rolls inclines upwardly toward the center from each end, forming wedging surfaces. Hence any attempt to move the slide as an effort 105 applied through the link 2 will force a wedging surface up under either roll and consequently wedge the roll between the block and the track and prevent any movement. On the other hand, if the carriage is moved 110 by the handle 15, the turned-in lug 16 (Fig. 7) will move the roll 14 and through it thrust upon the prow of the slide and in no way cause the same to bind against the track. The consequence is that a clutch is afforded 115 which locks when actuated through effort applied to the window and which runs free when effort is applied through the handle. It will be apparent that the lifting and 120 lowering can be done by the levers alone, omitting the check link *n* and the lower end of the lever *m*. In this event it will be advisable to omit the link *q* and attach the lever *m* directly to the window rail *s*. However, the check link *n* and the extended lever 125 *m* play a very important part in an improved operation of lifting a window with levers. If the check link and link *q* be omitted, the movement of the levers is in part guided by the travel of the window in 130

its ways. Consequently there is side thrust of the window upon its ways due to side thrust upon the window imposed by the levers. The function of the check link *n* is much the same as that of a check link in a weighing scale where this member keeps the platform stem vertical. However, in the window regulator the check link *n* has primarily the function of causing the upper 10 end of the lever *m* to travel in a substantially vertical path. The pivot 20 describes a fixed arc. Without the check link *n* the link *q* on the first thrust movement of the lever *m* would swing through 90° until it jammed 15 against the bottom of the window rails; in the first pull of the lever *m*, in lowering the window, the link *q* would simply swing into straight line position with the lever *m*. Either of these occurrences would tend to 20 cramp the window in its ways. The check link by reason of swinging in a determined arc compels the end of the lever *m* to travel in a prescribed path and because of the loose connection through the link *q* with the window 25 takes the stresses off the window frame and transfers them to the check link where they may be taken care of with a minimum of friction and loss of power. It will be found by experimentation that almost any 30 length of check link will cause the end of the lever to travel through almost a straight vertical line within a given range of movement. Of course, the very best length of check link and placement will depend altogether upon variable factors, such as the 35 length of the levers *m* and *h*, and hence, it will have to be in each case determined by a cut and try method.

The handle 15 is offset over the garnish 40 rail 17 and slides therewith. Hence this fixture in no way interferes with any of the fittings in the car.

What I claim is:

1. In a window regulator, the combination 45 of a frame, a window slidable vertically in the frame, a pair of toggle levers for lifting the window having a fixed pivot at one end of the toggle, a second pair of toggle arms by which the toggle levers may be straightened or broken and pivoted on the same 50 fixed pivot and operatively engaging the first toggle arms near their knee, and means for operating said second pair of toggle arms.
2. In a window regulator, the combination 55 of a frame, a window slidable vertically therein, a transverse track, a slide slidable thereon, a system of levers between the slide and the window for lifting or lowering the 60 same, a handle for operating the slide, and clutch devices in connection with said slide and handle which jam and lock when effort is applied through the lever system and which allow the slide to run freely when 65 effort is applied by the actuating handle.

3. In a window regulator, the combination of a frame, a window slidable vertically therein, operating parts for raising and lowering the window, and means for actuating the operating parts including a transverse 70 track, a carriage thereon, a slide carried along on the track with the said carriage and connected with the operating parts, and clutch members between the slide and the carriage which jam against the track when 75 effort is applied through the operating parts and which run freely when effort is applied through the carriage.

4. In a window regulator, the combination of a frame, a window slidable vertically 80 therein, operating parts for lowering or lifting the window, and means for actuating the same including a transverse track, a carriage slidable on the track, a slide loosely carried along by the carriage and connected with the operating parts and provided with wedging surfaces and rolling members between the wedging surface of the slide and the track whereby effort applied through the operating parts and slide tends to jam the rolling members against the track by bringing the wedging surface thereunder, while effort applied through the carriage causes the slide to run freely on the track to actuate the operating parts. 90

5. In a window regulator, the combination of a frame, a window slidable vertically therein, operating parts for lifting or lowering the window, and means for actuating the same including a channel-like track with 100 oppositely - directed outwardly - extending flanges, a carriage comprising turned-over hooks or lugs adapted to engage around the flanges to lock the carriage in place, a slide having raised ends or prows loosely engaged 105 within the carriage and connected with the operating parts and provided with wedging surfaces, and rolling members between the wedging surfaces and the raised ends or prows of the slide, and a driving lug extending laterally from the carriage to engage between the rolling members whereby effort applied to the operating parts jams the slide and rolling members in the channel while effort applied through the carriage drives 110 the slide freely through either roll.

6. In a window regulator, a supporting plate, a hub journaled in the supporting plate, a coiled counterbalancing spring having its inner end secured to the hub, an operating part of the window regulator mechanism secured to the other end of the counterbalancing spring, and rotatable means movable in and out of position for holding the rotatable hub in various positions of adjustment to permit the tightening and loosening of the counterbalancing spring. 120

7. In a window regulator, the combination of a supporting plate, a hub journaled therein provided with teeth on its periphery 130

having gullets therebetween, and a catch in the form of a disk rotatably secured to the plate and having a flattened side adapted to lock the hub when the rounded portion of 5 the disk engages between the teeth and adapted to permit the hub to be rotated for adjustment when the flattened side is adjacent the teeth, a counterbalancing spring coiled about the hub and having its inner 10 end secured thereto, and a window operating part secured to the opposite end of the counterbalancing spring.

8. In a window regulator, the combination of a lockboard having a bored portion, 15 a cup-like supporting plate set in the bored portion of the board and having its rear exposed through the front of the board, a hub journaled in said cup-like supporting plate and having on the outside of the cup a 20 flange formed into teeth, and a catch pivoted on the outside or rear of the cup adapted to engage between the teeth but removable from the teeth by rotation, a counterbalancing spring wound about said hub and 25 having its inner end secured thereto, and a window operating part secured to the other end of the spring.

9. In a window regulator, the combination of a frame, a window slidable vertically 30 therein, a pair of toggle levers for lifting the window, one of the toggle levers having an extension at the knee end of the lever, a check link secured to said extension, and means for breaking or straightening the 35 toggle levers to raise or lower the window.

10. In a window regulator, the combination of a window guided vertically, a lever immediately under the window for thrusting or pulling said window to raise or lower 40 the same, and means operating on the other end of the lever to guide the same so that the thrust of the lever is substantially a vertical thrust on a single straight line.

11. In a window regulator, the combination of a window guided vertically, a lever 45 immediately under the window, operating parts connected therewith for raising and lowering the window, and a check link having one end secured to a stationary pivot 50 and operating in connection with the end of said lever remote from the window to guide the thrusting end of the lever in a substantially vertical path in a single straight line.

55 12. In a window regulator, the combination of a window guided vertically, a lever for thrusting the same upwardly or pulling the same downwardly, operating parts connected with the lever for furnishing the power, and a check link secured to the end of the lever opposite the thrusting end for guiding the lever so that its thrusting end travels in a substantially vertical straight line.

65 13. In a window regulator, the combina-

tion of a window guided vertically, a link secured to the bottom thereof, a lever secured to the end of the link for thrusting the window upward or pulling the window downward, operating parts for raising and lowering the window, and guiding means on the opposite end of the lever causing the thrusting end of the lever to run through a substantially straight vertical path and thereby keep the connecting link with the window in substantially vertical position.

14. In a window regulator, the combination of a window guided vertically, a link secured to the bottom of the window, a lifting lever secured to the link at one end, a 80 check link secured to the opposite end of the lever to cause the thrusting end of the lever to describe substantially a vertical path, and means for operating the said lever.

15. In a window regulator, the combination of a window guided vertically, a lever having a connection with the window so that the said lever end may move slightly with respect thereto, means for swinging the lever, and a check-link on the opposite end of 90 the lever for causing the thrusting end of the lever to move in a substantially vertical line.

16. In a window regulator, the combination of a window guided vertically, a single 95 pair of toggle arms *m* and *k* for raising or lowering the window, the toggle arm *k* being provided with a fixed fulcrum, and means for folding or straightening out said toggle arms including a pair of toggle arms *y* 100 and 1 operating at one end on a fixed fulcrum.

17. In a window regulator, the combination of a window guided vertically, a pair 105 of toggle arms *m* and *k* for raising and lowering said window, the toggle arm *k* being provided with a fixed fulcrum, and means for folding or straightening out said toggle arms including a pair of short toggle arms *y* and 1, the latter of which is part of the 110 bell crank lever *w*.

18. In a window regulator, the combination of a window guided vertically, a slide 115 for actuating purposes, and a system of levers and links connecting the slide with the window arranged so that when the window is in its lowermost position the link immediately connected with the slide is on substantially a dead center thrust position as regards any back thrust through the levers and thereby locking the window in its lowermost position.

19. In a window regulator, the combination of a window guided vertically, a slide 125 slidable transversely of the window, a system of levers and links connecting the slide with the window and arranged to set one of the members at a substantially dead center position to any back thrust when the window is in its lowermost position.

20. In a window regulator, the combination of a window guided vertically, a pair of toggle arms *m* and *k* for raising and lowering the window, the toggle arm *k* being provided with a fixed fulcrum, a set of levers *y* and *w*—1 for folding or straightening the toggle arms, a slide running transversely of the window for actuating the parts, and a link 2 connecting the slide with the end of the lever *w*—1, said parts arranged so that when the window is in its lower position 20 the link 2 is on substantially a dead center thrust position as regards any back thrust through the levers.
21. In a window regulator, the combination of a window guided vertically, a pair of toggle arms *m* and *k* for raising and lowering the window, the toggle arm *k* being pro-

vided with a fixed fulcrum, a set of levers *y* and *w*—1 for folding or straightening the 15 toggle arms, a slide running transversely of the window for actuating the parts, and a link 2 connecting the slide with the end of the lever *w*—1, said parts arranged so that when the window is in its lower position 20 the link 2 is on substantially a dead center thrust position as regards any back thrust through the levers.

In testimony whereof I affix my signature.

ERNEST E. HEINTZ.
